CLAIM

The ornamental design for an automobile tail light, as shown and described.

DESCRIPTION

FIG. 1 is a perspective view of an automobile tail light;

FIG. 2 is a front view thereof;

FIG. 3 is a side view thereof;

FIG. 4 is a top view thereof; and,

FIG. 5 is a bottom view thereof.

The broken lines are included to show environmental structure and form no part of the claimed design.

The design envisioned contains a second portion whose image is mirror symmetrical to the one shown.
